VEHICLE LIFT

Frank D. Freudenthal and Gilbert W. Gaarder, St. Joseph, Mo., assignors to Gray Manufacturing Company, Inc., St. Joseph, Mo., a corporation of Missouri

Filed Oct. 6, 1967, Ser. No. 8,884

Term of patent 14 years

(Cl. D41—1)

FIG. 1 is a side elevational view illustrating the vehicle lift;

FIG. 2 is a top plan view thereof;

FIG. 3 is a bottom plan view thereof;

FIG. 4 is a front elevational view thereof; and

FIG. 5 is a rear elevational view.

The side opposite to that shown in FIG. 1 is the same in appearance as that shown in FIG. 1.

We claim:

The ornamental design for a vehicle lift, as shown and described.
